UNITED STATES PATENT OFFICE.

WILHELM L. LARSON, OF OSLO, MINNESOTA.

CIRCUIT BREAKER.

Application filed June 7, 1922. Serial No. 566,518.

To all whom it may concern:

Be it known that I, WILHELM L. LARSON, a citizen of the United States, residing at Oslo, in the county of Marshall and State of Minnesota, have invented new and useful Improvements in Circuit Breakers, of which the following is a specification.

This invention relates to improvements in electric generators.

10 An object of the present invention is the provision of means for automatically stopping the operation of a generator in the event of interruption of flow of current between the generator and another electric 15 device, for example, a battery, whereby burning of the generator windings will be prevented, the invention being especially useful upon automobiles.

Another object of the invention is the 20 provision of a device for this purpose, which may be readily adjusted so that operation of the generator may be again resumed, when desired.

With the above and other objects in view, 25 the invention further includes the following novel features and details of construction, to be hereinafter more fully described, illustrated in the accompanying drawings and pointed out in the appended claim.

30 In the drawings:—

Figure 1 is an elevation of the invention with the cover removed and showing the position of the parts during normal flow of current.

35 Figure 2 is a similar view showing the position of the parts when operation of the generator has been interrupted.

Figure 3 is a view at right angles to Figure 1.

40 Figure 4 is a top plan view of the same.

Referring in detail to the drawings, wherein like characters of reference denote corresponding parts, the reference character 11 indicates the circuit breaker which constitutes the present invention.

This circuit breaker comprises an insulating base 12 and a cover 13, which may be removably secured thereto in any desired manner. Located within the cover 13 and secured to the base 12 is an electromagnet having one terminal of its winding 14 connected to a binding post 15, while the opposite terminal of the said winding is connected to a plate 16 which is secured to the end of the magnet and which has extending therefrom an arm 17, the latter being pro-

vided with an offset portion 18. The outer end of the arm 17 has pivotally connected thereto as shown at 19 a substantially L-shaped lever one arm of which is bifurcated to provide spaced parallel arms 20, while the opposite arm 21 is movable into and out of contact with the offset portion 18 of the arm 17, the said offset portion serving to limit the pivotal movement of the lever 20 in one direction.

Pivots secured between the spaced parallel arms 20 of the L-shaped lever as shown at 22 is a contact arm 23, whose free end is adapted to engage a stationary contact 24 mounted upon the base 12, being secured to the said base as by a binding post 25. The bifurcated arm of the L-shaped lever is connected to the contact arm 23 by means of a spring 26, herein shown as a coiled spring, the connection between this spring and the contact arm 23 being of a flexible character, as indicated at 27. The purpose of this form of connection 27 is to permit of the latter being bent, whereby the tension of the spring 26 may be regulated. When the pivotal connection 22 is moved to either side of the center, the spring 26 will function to hold the arm 23 and its connected lever against accidental movement.

The connection 22 between the arm 23 and the bifurcated end of the lever is preferably in the form of a link 28 and also connected to this link is one end of an armature 29, the opposite end of which has a flexible connection 30 with an extension 31 at one end of the electro magnet. Extending from the contact arm 23 is a rod or finger 32, which projects through an opening in the armature 29 and has its extremity bent to form a stop 33, whereby outward movement of the contact arm 23 will be limited.

The binding post 15 is connected by means of a conductor with one of two armature brushes of the generator, while the other binding post 25 is connected by a conductor of the winding or said brush, so that when the generator is operated, current will pass from the brush through the conductor, the binding post 25, the stationary contact 24, the contact arm 23, the L-shaped lever, the pivoted arm 17, the plate 16, the winding 14, the binding post 15, the other conductor to the field winding of the generator.

When the generator is connected to a storage battery in the usual manner, current will flow through the winding 14 and

- as this current will pass into the battery, its strength will not be sufficient to energize the electromagnet and the armature 39 will not be attracted, so that the parts will
- 5 remain in the position shown in Figure 2. If for any reason current ceases to flow from the generator to the battery, it will build up in the winding 14 sufficiently to energize the magnet and the armature 14 will then be attracted and the pivot 22 moved to the opposite side of the center. The tension of the spring 26 will then cause the free end of the contact arm 23 to move away from the stationary contact 24, so that flow of current
- 10 will cease, and operation of the armature stop. This will prevent damage to the generator due to current backing up in the field windings. When it is desired to again operate the generator, the arm 21 will be forced downward into contact with the offset portion 18 of the hinged arm 17 to move the pivot 22 upon the opposite side of the center and cause the free end of the contact arm 23 to engage the stationary contact 24.
- 15 20 25 The invention is susceptible of various changes in its form, proportions and minor
- details of construction and the right is herein reserved to make such changes as properly fall within the scope of the appended claim.
- 30 Having described the invention what is claimed is:—
- A circuit breaker comprising an electromagnet, a stationary contact arranged alongside the magnet, an armature also disposed alongside the magnet and interposed between same and stationary contact, a plate connected to and extending from one end of the magnet, an L-shaped lever pivotally mounted on said plate, a contact arm for cooperation with the stationary contact, a link on the armature and pivotally connected to the L-shaped lever and the contact arm, a finger on the contact arm and extending through an opening in the armature and having a stop portion arranged to cooperate with the armature and a retractile spring interposed between and connected to the contact arm and the L-shaped lever.
